Application May 14, 1941, Serial No. 393,466
In Canada May 20, 1940

11 Claims. (Cl. 222—456)

Our invention relates to improvements in containers and more particularly to those of the carton type incorporating a pouring and measuring means for the contents, and an object of the invention is to devise a container which, while permitting the combined pourer and measurer to be disposed entirely within the confines of the container, will lend itself readily to economical production such as is essential in carton type commodity containers and will be capable of being collapsed or packed flat instead of set up during shipment and storage prior to use.

A further object is to originate a container in which the measurer or contents receiving pocket will automatically position itself therein upon the container being transposed from its collapsed position into its set-up position.

Yet other objects are to provide a container in which it and its pourer and measurer are fabricated integrally from a single sheet of paper or cardboard, and in which the resultant container may be filled and sealed by the orthodox machines at present in use for containers of this type.

With the above and other objects in view which will hereinafter appear as the specification proceeds, our invention, in its preferred embodiment, consists of the construction and arrangement all as hereinafter more particularly described and illustrated in the accompanying drawings in which—

Fig. 1 represents a plan view of the blank from which the container is formed.

Fig. 2 is an edgewise view of the blank illustrated in Fig. 1.

Fig. 3 is a similar view to Fig. 2 only showing a side flap constituting a part of the combined pourer and measurer infolded onto the part of the blank forming one of the end walls of the container and gummed thereto.

Fig. 4 is an enlarged plan view of the formed up container with the ends open and in the collapsed or flat position, the dotted lines indicating the container partially opened up and showing the actuation of the combined pourer and measurer into its operative position.

Fig. 5 is a side view of the upper part of the formed up container in the position illustrated in Fig. 4.

Fig. 6 is an enlarged plan view of the container in its fully opened up position instead of that shown in Fig. 4.

Fig. 7 is a plan view of the container with the top closed and drawn to the same scale as Fig. 6.

Fig. 8 is a perspective view of the upper part

of the container closed at its top but having an end portion of the lid turned down into the container to constitute a baffle for the combined pourer and measurer.

Fig. 9 is a further enlarged vertical sectional view of the container showing it with the top closed as in Fig. 7, such section being taken on the line 9—9 of that figure.

Fig. 10 is a similar enlarged section of the container to Fig. 9 only showing the portion of the lid turned down into the container as illustrated in Fig. 8.

Fig. 11 is a fragmentary elevation of end wall 5 of the container blank, showing an alternative construction of the blank for the pouring device, and

Fig. 12 is a fragmentary section taken through a part of the set-up container showing the co-operating relation between the vertical baffle of the container.

Like characters of reference indicate corresponding parts in the different views of the drawings.

In the embodiment of our invention as illustrated the container is of the rectangular paper carton type with flap closures for both top and bottom and adapted to be collapsible so that it may be packed flat prior to being used. When required for use the container is designed to be opened up and filled and sealed by standard machines ordinarily employed for packaging cartons of this type. It comprises an integral blank of paper or cardboard A suitably scored and cut to form it into side wall portions 1 and 2 separated by an end wall 3, the opposite side edges of the portions 1 and 2 to those adjacent to the portion 3 having respectively similar end wall portions 4 and 5. Top and bottom end flaps 6 and 7, 8 and 9, 10 and 11, and 12 and 13 are provided respectively on the upper and lower ends of the portions 1, 3, 2 and 5. The construction so far is orthodox in any carton of the above referred to type.

A short distance from the end of the flap 6 adjacent to the end wall 4 is an arcuate incision 14 located intermediately of the width of the flap and its ends connected to lateral score lines 15 extending to the side edges of the flap 6. The score line 15 extending to the flap side edge adjacent the side wall 1 connects with a perforation line 16 at right angles thereto continuing to the adjacent corner of the end wall 4.

A lateral score line 17 positioned the same distance from the end of the flap 10 adjacent the flap 12 as the score lines 15 are spaced from the

end of the flap 6 adjacent the end wall 4 extends from side to side of such flap 10 and joins a perforation line 18 at right angles thereto and continuing to the adjacent corner of the end wall 5. A continuation 19 of the perforation line 18 extends laterally across the junction of the flap 12 with the end wall 5 and a further line of perforations 20 very substantially weakening the flap 12 intermediately extends laterally there-across an equal distance from the perforation line 19 to the distance the score lines 17 and 15 are from the above referred to ends of the flaps 10 and 6 respectively.

An additional rectangular flap 21 is provided extending out from the free edge of the end wall 5 and its upper edge is preferably coincident with the perforation lines 18 and 19. Such flap 21 is only joined to the end wall 5 at its lower portion below a transverse score line 22 disposed intermediately of the height of such flap 21. From a score line 23 extending from the junction of the free edge of the flap 21 with the score line 22 to the corresponding upper corner of the flap 21 a further flap 24 extends outwardly and inclinedly downwardly towards its free end edge. The outer portion of such flap 24 is rectangular and corresponds in width to the flap 21 and the end wall 5. A score line 25 extends upwardly from the junction of the score line 22 with the lower end of the score line 23 and parallel to the free end edge of the flap 24 and a second upwardly extending score line 26 substantially bisects the angle formed by the score lines 23 and 25, the lines 23, 25 and 26 forming a foldable web connection between the flaps 21 and 24 which constitute in effect joining extensions of said flaps.

In forming up the container the flap 21, which has previously had the flap 24 folded onto it along the score line 26, is folded onto the end wall 5 and the part below the score line 22 is gummed to such end wall, the flap 24 which is interposed between the flap 21 and the end wall 5 is also gummed to the end wall 5, the parts 27 and 28 of such flap 24 being in superimposed relation and lying against the adjacent side wall 2 as illustrated in Fig. 3. The container is then suitably folded on the score line between side wall 2 and end wall 3 so that the side wall 2 and end wall 5 together with the folded and glued flaps 23 and 21 are superimposed on end wall 3 and side wall 1. Then end wall 4 is folded over and glued onto end wall 5, all of which can be done on a standard folding and gluing machine.

When it is desired to use the container it is only necessary to set it up in rectangular form when the upper part of the flap 21 will be automatically swung out as illustrated in Figs. 4, 6, 8, 9 and 10 wherein it is inclined upwardly and inwardly from the end wall 5 about the score line 22 constituting a baffle B having its upward edge disposed in spaced relation to the top of the container and with the end wall 5 forming a pocket C for entrapping a predetermined quantity of the contents of the package. In this connection, as noted particularly in Fig. 4, the extensions 27 and 28 constitute a foldable web between the flap 21 and flap 24 and in the collapsed position of the container are folded one upon the other and lie between the side walls 1 and 2 of the container, the baffle forming flap 21 lying upon the end wall 5. Since the extension 28 connects directly with the flap 24 which is glued or otherwise secured to the end wall 5 and the folded extensions 28 and 27 overlie the side wall 2 when the container is in its collapsed position, it will be appreciated that

when the container is swung to set-up position, the side wall 2 of the container engaging first of all the extension 28 and then the point of folding between the extension 28 and 27 will finally press upon the fold between these extensions and cause them to become aligned with one another, thus automatically causing the baffle forming flap 21 to assume normal set-up position when the container is set up from its collapsed position. The extensions 27 and 28, when the flap 21 is in the baffle forming position, are in the same plane instead of super-imposed and side wall 2 of the container in bearing engagement with the extensions maintaining them in the same plane when the container is in set-up position, and such bearing or pressure engagement serves to hold the baffle in its normal set-up position.

The top of the container is now closed by in-turning the end flaps 8 and 12 and then the flaps 10 and 6, the flap 6 lying uppermost and such flaps being gummed together to form an effective top closure for the container. The container is then filled and the lower flaps 9 and 13 and 7 and 11 inturned and secured together to form the bottom closure of the package.

Alternatively in some methods of packaging the bottom may be closed first and the top last after the contents have been inserted.

When it is desired to dispense the contents of the package the perforation lines 16, 18 and 19 are completely severed by the user, the tab 29 resulting from the incision 14 is pried up and held in position by the fingers while the end portions of the flaps 6, 10 and 12 are pushed down into the position illustrated in Figs. 8 and 10 wherein such end portions form a laminated baffle D depending into the pocket C in spaced relation to the baffle B and the end wall 5 being interposed between these two parts. A discharge passageway E is constituted between the baffle D and the end wall 5. The buckling of the baffle D is prevented by the above referred to holding of the tab 29 by the fingers, and the prying up of such tab tends to start the turning down of the baffle D. Such baffle is sufficiently rigid to remain substantially in its proper position when once bent down into such position.

The combined pourer and measurer in the container functions on the same principle as the structures disclosed and claimed in our United States application Serial No. 314,522, filed January 18, 1940, and in our copending United States application Serial No. 331,196, filed April 23, 1940. When the package is primarily inverted so that the corner with the discharge passageway E is lowermost a predetermined amount of the contents such as powdered soap, or any reasonably fine comminuted material flows in between the baffle B and the baffle D. Upon the container being restored to its normal upright position such quantity of material is entrapped and falls down into the pocket C. When the container is again inverted this same quantity of material is discharged through the passageway E. As this particular quantity of material is discharged another and substantially identical amount flows in between the two baffles. Thus alternately inverting and turning the package upright successively dispenses substantially equal quantities of material from the container until the same has been entirely emptied.

It is obvious that by changing the length and/or the inclination of the baffles B and D, the amounts

of commodity dispensed from the container can be varied.

An alternative form of construction such as illustrated in Figs. 11 and 12 might be employed. This form of construction is substantially the same as that previously described but in addition to the flap 21, the extensions 27 and 28 and flap 24, there is provided an extension 27a which connects with a portion of flap 21 along the fold line between flap 21 and end wall 5, the extension being cut from the material of end wall 5.

The upper and lower edges 27b and 27c of the extension 27a are cut on an incline as shown, the incline of the lower edge 27c being such that when the container has been moved from its collapsed to its set-up position and the baffle B, formed by the flap 21, is disposed in its inclined operating position, the edge 27c of the extension 27a will abut the end wall 4 and will thus serve as a means of holding the baffle B more firmly.

In all other respects the baffle B and its associated structure operate in exactly the same manner since the additional extension 27a will, in the collapsed position of the container, lie in its normal recess in the end wall portion 5 and will swing out from said recess when the baffle B is moved to its operative position at the time that container is being set-up from its folded position. In the operative position, as is apparent, the extension 27a will lie along the interior surface of side wall 1 of the container parallel thereto and parallel to the extensions 27 and 28 which then lie in a common plane and along the interior surface of side wall 2 of the container, the extension 28 normally being glued to the side wall 2 of the container and forming the means for causing the baffle B to assume its inclined position as the container is set-up from its collapsed position.

The extension 27a may also be formed with a notch 27d such that when the baffle D is turned downwardly as shown in Fig. 12, the lower edge of this baffle will enter the notch and form a further means of reinforcing the baffle B when it is in its inclined operative position.

Ordinarily the flap 24 may be of a width corresponding to the width of end wall 5. However, where the construction is so formed as to include the extension 27a cut out from the end wall 5 the flap 24 is made narrower, so that it will lie on the end wall 5 alongside of the extension 27a or the cut-out in wall 5 from which the extension is formed.

From the above description it will be apparent that we have devised a simple and effective container for commodities incorporating a combined pourer and contents measure which can be manufactured at practically the cost of the present package of the same type and unequipped with such improvement. Furthermore, our container can be filled and sealed by existing equipment employed for this purpose.

Many modifications may be made in the invention without departing from the spirit of the same or the scope of the claims. For instance, the sequence of folding the several parts of the blank to form up the container may be varied at will to suit the operation of the machines used.

What we claim as our invention is:

1. In a container of the rectangular set up carton type including side and end walls and a top closure, an inwardly and upwardly extending transverse baffle between the side walls having its lower end in abutment with one end wall, and its upper end in spaced relation to the closure whereby a contents receiving pocket is formed between the baffle and such end wall, a flap associated

with said baffle and secured to such end wall, and a foldable web extending between one side of the baffle and the corresponding side of the flap, said foldable web and baffle being collapsible with the container when the latter is collapsed, said flap and web causing said baffle to assume an operative set-up position when said container is set up from collapsed position.

2. In a container of the rectangular set up carton type including side and end walls and a top closure, an inwardly and upwardly extending transverse baffle between the side walls having its lower end in abutment with one end wall and its upper end in spaced relation to the closure whereby a contents receiving pocket is formed between the baffle and such end wall, a flap associated with said baffle and secured to such end wall, and a foldable web extending between one side of the baffle and the corresponding side of the flap, said side and end walls, top closure, baffle, flap and web being formed integrally from a single sheet of paper or cardboard, said foldable web and baffle being collapsible with the container when the latter is collapsed, said flap and web causing said baffle to assume an operative set-up position when said container is set up from collapsed position.

3. In a container of the rectangular set up carton type including side and end walls and a top closure, an inwardly and upwardly extending transverse baffle between the side walls having its lower end in abutment with one end wall and its upper end in spaced relation to the closure whereby a contents receiving pocket is formed between the baffle and such end wall, a flap secured to such end wall, a foldable web extending between one side of the baffle and the corresponding side of the flap connecting said baffle and flap together, said baffle being collapsible upon said end wall of the container, and a downwardly directed extension on the baffle secured to such end wall said flap and web cooperating with walls of the container to move said baffle to set-up position when the container is set up from collapsed position.

4. In a container of the rectangular set up carton type including side and end walls and a top closure, an inwardly and upwardly extending transverse baffle mounted solely upon an end wall and between the side walls having its lower end in abutment with one end wall and its upper end in spaced relation to the closure whereby a contents receiving pocket is formed between the baffle and such end wall, a flap secured to such end wall, a foldable web extending between one side of the baffle and the corresponding side of the flap connecting said baffle and flap together, said baffle being collapsible upon said end wall of the container, and a downwardly directed extension on the baffle secured to such end wall, said side and end walls, top closure, baffle, baffle extension, flap and web being formed integrally from a single sheet of paper or cardboard.

5. In a container of the set up carton type of rectangular form with side and end walls and incorporating a fractional contents measuring device comprising a transverse baffle mounted solely upon an end wall and extending upwardly and inwardly between the side walls from an intermediate point in the height of said end wall towards the container top and its upper edge in spaced relation thereto whereby a contents receiving pocket is formed between the baffle and such end wall, and foldable means in connection with the baffle whereby said baffle may be collapsed when said container is collapsed, said means bearing against a side wall when the container is in

its set up position for holding the baffle substantially rigid.

6. In a container of the set up carton type of rectangular form with side and end walls and incorporating a fractional contents measuring device comprising a transverse baffle extending upwardly and inwardly between the side walls from an intermediate point in the height of one end wall towards the container top and its upper edge in spaced relation thereto whereby a contents receiving pocket is formed between the baffle and such end wall, said baffle normally lying against said end wall when the container is in its collapsed position, means for automatically actuating the baffle from its folded position to an open operative position as the container is set up from its collapsed position and means in connection with the baffle bearing against a side wall when the container is in its set up position for holding the baffle substantially rigid.

7. A container as claimed in claim 6, in which the means for holding the baffle substantially rigid comprises an extension along one side of the baffle having an edge cut at an incline to engage a side wall when the baffle is in pocket forming position.

8. A container as claimed in claim 6 in which the baffle is formed with an extension designed to project from one side thereof, said extension being notched and a tab formed in the container top swingable inwardly of the container to form a discharge opening therein and engageable in the notch of the extension, said tab and notch forming a means of holding the baffle substantially rigid, said tab forming a second baffle cooperating with the first mentioned baffle in the discharge of the contents of the container.

9. In an integral paper or cardboard blank for forming a rectangular set up carton type container incorporating a contents measuring de-

vice, rectangular side and end wall portions, a flap comprising an upper and lower part extending laterally from the free side edge of one end wall portion and attached thereto only by the lower part of said flap, and a downwardly inclined portion on said flap extending from the outer edge of the upper unattached part of the flap.

10. In an integral paper or cardboard blank for forming a rectangular set up carton type container incorporating a contents measuring device and, rectangular side and end wall portions for the container, a flap comprising an upper and lower part extending laterally from the free side edge of one end wall portion and attached thereto only by the lower part of said flap, and a downwardly inclined portion on said flap extending from the outer edge of the upper unattached part of the flap, said downwardly inclined portion comprising a rectangular end portion and a scored triangular web portion joining the rectangular end portion to the upper part of the flap.

11. In a container of the set up carton type of rectangular form with side and end walls and incorporating a fractional contents measuring device comprising a transverse baffle extending upwardly and inwardly between the side walls from an intermediate point in the height of one end wall towards the container top and its upper edge in spaced relation thereto whereby a contents receiving pocket is formed between the baffle and such end wall, means for securing said baffle to said latter end wall and means in connection with said baffle disposed between a side wall and said latter end wall and engageable by said latter side wall for causing said baffle to assume an operative set up position when said carton is set up from collapsed position.

GEORGE ALEXANDER RAMSDEN,
GEORGE JOHN RUSSELL RAMSDEN.
